UNITED STATES PATENT OFFICE.

ABNER LINWOOD HOLTON, OF NORFOLK, VIRGINIA.

NOTE-BOOK.

SPECIFICATION forming part of Letters Patent No. 700,648, dated May 20, 1902.

Application filed January 9, 1902. Serial No. 89,075. (No model.)

To all whom it may concern:

Be it known that I, ABNER LINWOOD HOLTON, a citizen of the United States, residing at Norfolk, in the county of Norfolk and State 5 of Virginia, have made certain new and useful Improvements in Tablets, of which the following is a specification.

My invention is an improvement in tablets in the form of note-books, and especially in 10 books of such character designed for use by stenographers in taking notes; and the invention consists in certain novel constructions and combinations of parts, as will be hereinafter described and claimed.

15 In the drawings, Figure 1 is a perspective view of my note-book as in use. Fig. 2 is a detail sectional view, the base-plate being partially broken away. Fig. 3 is a detail perspective view of the base-plate, showing the 20 latch-plate in unlocked position and one of the bows detached. Fig. 4 is a bottom plan view of the base-plate and latch-plate, showing the ends of the bows secured by the latch-plate. Fig. 5 is a detail perspective view of 25 a portion of the base-plate with one of the fixed posts in place and differing slightly in construction from the posts shown in Fig. 3. Fig. 6 is a detail perspective view of one side of one of the bows formed to fit the post shown in Fig. 5; and Fig. 7 is a detail bottom plan view, partly broken away, showing a somewhat different form of latch from that shown in Fig. 3.

30 The note-sheets A may be ruled, as is usual for stenographic use, and are provided with perforations a to receive the fixed posts and the bows. The fixed posts B are mounted on or otherwise suitably secured to the base-plate C and are made in cross-section in the 35 form of segments of a circle and for interlocking engagement with the bows D. The posts B are arranged adjacent to perforations E, formed through the base C and through which project the ends of the bows D, the 40 latter being provided with notches d for engagement by the latch-plate operating beneath the plate C. In Figs. 1, 2, and 3 the bow and posts are formed, as best shown in Fig. 3, the upper ends of the posts B being notched at 45 b and the bows D being formed with the tenons D' to fit along the inner sides of the posts B, the shoulders d' at the upper ends of the

tenons D' being formed to fit in the notches b in the upper ends of the posts B, thus interlocking the bows D and the posts B, as will be understood from Fig. 3. The bows D project at their ends in position for engagement by the latch-plate F, which slides longitudinally in a dovetail groove in the under side of the base-plate C and is arranged to enter the 55 notches d when the parts are in the position shown in full lines, Fig. 4, and has notches f, which may be adjusted to coincide with the openings E in the base-plate when it is desired to apply or remove the bows D. The plate 60 F may be easily adjusted longitudinally in the guide-groove C' of the plate C, and its movements may be limited by a stop F', projecting through a slot C' in the base-plate C, as shown in Fig. 3. By using the plate F, I 65 am able to lock both bows by the same latch. It will be understood, however, that independent latches may be used for each bow, and where desired the latch may be a pivoted plate, as shown in Fig. 7, in which the plate 70 G is pivoted at G' between its ends and may be adjusted at its opposite ends into and out of engagement with the ends of the bows. In Fig. 3 the bow is interlocked to the fixed 75 posts by notching the upper ends of the posts 80 and forming the bows with projections to enter said notches. This interlocking, however, may be accomplished in different ways, such as shown in Figs. 5, and 6, in which the post is grooved longitudinally at H, and the bow is 85 provided alongside its notched tenon with a tongue or rib I to enter the groove H.

In Fig. 1 I illustrate a base-board J, which is as wide as the base-plate and as long as the note-sheets and is designed for use when 90 it is desired to furnish a stiff backing for taking dictation standing or in any place where a desk is not convenient. This base-board may be of metal, wood, or other suitable material and is preferably detachably 95 connected with the base-plate C, a convenient means for securing such end being illustrated in Figs. 1 and 2, wherein the base-board J is provided with an undercut groove J', extending across its face and receiving the 100 base-plate C, which extends at its opposite edge sufficiently beyond the post B to engage in the groove of the base-board J. The base-plate can be conveniently removed from the

groove in the base-board and turned end for end, this being especially desirable in reversing the base-plate when the stenographer has written through the book on one side of the sheets and desires to readjust the book to the base-board so the other sides of the sheets of the book may be written upon.

It will be noticed the fixed posts are important, as they hold the note-sheets together when the bows are removed as well as when the bows are locked to the base-plate, and when the bows are locked to the base-plate the posts B rendering the bows more substantial and improving their connection with the base-plate, the posts being immovable and the bows being interlocked with the posts as well as being latched in connection with the base-plate. It will also be noticed the notches b in the post B are made somewhat in the form of a saw-tooth and being entered by the projections d' prevent any displacement of the bows when the latter are secured by the latch devices before described. Furthermore, the form in cross-section of the tenons d' and the posts B is half-round, and when fitted together they form cylindrical posts, fitting the openings a in the note-sheets. This cylinder is larger than the diameter of the bow-rod at the crown of the bows in order to facilitate the adjustment of the note-sheets from side to side of the bows, this being effected by making the bows with their crown portions reduced in thickness.

As shown in Figs. 1, 2, 3, 4, and 5, the opposite edges of the base-plate C are beveled or sloped off to an edge, this being desirable to avoid any abrupt bending of the note-sheets where they overlie the edges of the base-plate.

Having thus described my invention, what I claim as new, and desire to secure by Letters Patent, is—

1. The improvement in note-books herein described, comprising the base-plate sloped or beveled off at its opposite edges, provided with openings through which the ends of the bows may be passed and with fixed posts adjacent to said openings, the bows fitting alongside said fixed posts, and devices for securing the bows in connection with the base-plate, substantially as set forth.

2. In a device, substantially as described, the combination with the base-plate, of the half-round posts thereon, the bows having half-round tenons lapping alongside the said posts, and means for securing the bows, substantially as set forth.

3. The combination with the base-plate, and the posts thereon, of the bows interlocking with the posts, and devices for securing the bows to the base-plate, substantially as set forth.

4. The combination with the base-plate having openings through which the ends of the bows may project, the bows projecting at their ends through said openings and latch devices for securing the bows to the base-plate, substantially as set forth.

5. The combination with the base-plate having openings for the ends of the bows, and the posts adjacent to said openings, of the bows lapping alongside the posts and projecting through the openings in the base-plate, and latch devices beneath the base-plate for securing the bows, substantially as set forth.

6. The combination with a base-plate having openings for the ends of the bow and posts adjacent to said openings, the bow fitting alongside and interlocking with the posts and projecting through the openings in the base-plate, and the latch-plate beneath the base-plate and movable into and out of engagement with the bow, substantially as set forth.

7. The combination with the base-plate and the posts thereon, and notched in their upper ends, of the bow provided at its ends with tenons fitting alongside the posts and at the upper ends of said tenons with shoulders having projections entering the notches of the posts, and means for securing the bow, substantially as set forth.

8. The combination of the base-plate provided with openings for the ends of the bow, the bow projecting at its ends through said opening, and the slide-plate beneath the base-plate and arranged to secure the bow, substantially as set forth.

9. The combination of the base-plate provided in its under side with a groove, and having openings for the ends of the bow, the bow projecting at its ends through said openings and the latch-plate operating in the groove in the under side of the base-plate and movable into and out of engagement with the bow, substantially as set forth.

10. The combination with the base-plate provided with openings for the bow and adjacent thereto with posts, the bow fitting at its ends alongside said posts and projecting through the openings in the base-plate, and the latch beneath the base-plate for securing the bow, substantially as set forth.

11. In a note-book, the combination of the base-board, provided with a transverse undercut groove, and the base-plate fitted to said groove and movable into and out of the same and provided with bows arranged transversely the length of the base-plate for securing the note-sheets, substantially as set forth.
